Inventor:

Albert C. Fischer

By *Bellard Moore*

UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

OAKUM PACKING

Application filed April 16, 1928. Serial No. 270,515.

This invention is a continuation in part of my copending application, Serial No. 56,084, filed Sept. 12, 1925, and relates to improvements in oakum packings and particularly to packings which are adaptable for use in connection with the laying of sewer pipe, calking sidewalk lights, ships and the like.

It has heretofore been the practice to utilize materials for packing purposes which are comparatively expensive, and one of the primary objects of my invention is to produce a packing material of economical construction and adapted to be used with equal, if not superior, effectiveness than packing materials which have to my knowledge heretofore been employed.

I have found that there is available considerable roofing felt, known as seconds, and scrap material, and by incorporating there-with a slight percentage of fibrous matter and bituminous material I have been able to form a mixture which has binding strength and which presents a very effective packing material. This material may be produced for example by mixing roofing scrap with a soft bituminous material of low melting point and then adding a certain percentage of fibrous material such as cocoanut fibre or any other suitable long vegetable fibre which will add to the binding strength of the material. After this has been thoroughly incorporated within the mass, said mass may be formed by suitable means into strands and a plurality of these strands may be twisted or intertwined to present a rope packing of desired size. Obviously the number of strands intertwined to produce the rope packing material will be determined by the size of material which is needed.

A more comprehensive understanding of my invention and the objects thereof will be obtained from the following detailed description when considered in connection with the accompanying drawing wherein:

Figure 1 is a perspective view of my improved packing as made in a single coiled strand or strip;

Figure 2 is an enlarged view in longitudinal section of a short length of one of the strands or strips;

Figure 3 is an enlarged sectional view taken transversely of one of the strands on the line 3—3 of Figure 2;

Figure 4 is a side elevational view of a fragmentary portion of a rope packing produced by intertwining five of the single strands;

Figure 5 is a transverse sectional view taken on the line 5—5 of Figure 4;

Figure 6 is a fragmentary side elevational view of a rope produced by intertwining three of the single strands; and

Figure 7 is a transverse sectional view taken on the line 7—7 of Figure 6.

Referring now to the drawing wherein like numerals have been employed to designate similar parts throughout the various figures, it will be observed that I have designated a strand of my improved packing material by the numeral 1 and in Figure 1 I have disclosed said strand in the form of a coil. By coiling the strands in this manner, said strands may be retained in a convenient position for shipment as well as for use. In Figures 4 and 5 I have disclosed a rope structure designated by the numeral 2, which is comprised of five individual strands, and in Figures 6 and 7 I have shown a similar rope construction designated by the numeral 2^a, said rope construction comprised of three intertwined strands.

In Figure 2 I have disclosed a section taken longitudinally of one of the strands 1 for the purpose of disclosing the internal structure thereof. It will be observed that this strand is comprised of finely divided material from roofing felt, seconds or scrap indicated by the numeral 3 and relatively long fibres 4, such as cocoanut fibres, sisal, long grasses or other fibrous material of considerable length. This finely divided material 3 and the relatively long fibres 4 are incorporated within suitable bituminous material of low melting point, which I have indicated by the numeral 5, Figure 2. In producing the strand material 1 just described, I mix roofing scrap or other suitable finely divided material in a heavy mixture and incorporate therewith soft bituminous material of low melting point, sufficient to make 100

the material adequately waterproof. I prefer to add thereto five (5%) percent of cocoanut fibre or other suitable long vegetable fibre which will add to the binding strength 5 of the material. This is thoroughly incorporated with a mixture and then rolled into strips or strands such as the strands 1. I have found that scraps of roofing material are sufficiently interwoven and shredded 10 when masticated in a mixer so that it flows smoothly and has substantial strength, especially when materials such as cocoanut fibre, sisal, long grasses or other fibrous material of considerable length is incorporated therewith. In order to preserve the strand material, said material may be treated with a 15 flux oil, an oil of low melting point asphalt, so as to maintain the material pliable and malleable at all times.

20 From the foregoing it will be understood that the individual strands may be formed into rope structures by merely intertwining or twisting together a plurality of strands as clearly shown in Figures 4 and 6. The individual strands or intertwined structures 25 may be formed into convenient coils similar to the manner in which other packing materials are formed and one of the outstanding characteristics of my improved packing material resides in its comparative cheapness 30 and its adaptability to a wide range of use as compared with other materials. By producing this bituminous strand material I have greatly facilitated the use thereof for 35 packing purposes in that the material may be formed into rope structures of varied cross sectional areas in accordance with the particular work with which the packing material is to be used. Thus for example in 40 employing my improved strand packing material for the packing of sewer pipes and the like one size of said material would be used, while the use of material for calking purposes on ships might require another size.

45 It will thus be apparent that my invention provides a very convenient and practical packing material in strand or rope form, which is adaptable for a wide range of sizes and which provides a very effective pack- 50 ing.

Although I have specifically set forth certain long fibres and finely divided fibrous materials which might be incorporated with bituminous material, it is to be understood 55 that the elements constituting my improved strand or rope packing material are not necessarily limited to the elements which I have mentioned specifically and therefore the invention should be limited only by the scope 60 of the appended claims.

Having thus described my invention, what I claim as new and desire to secure by Letters Patent is:

1. Packing material of the class described, 65 comprising a plastic rope-like strand which

includes a plastic mixture of finely divided fibres and plastic bituminous material, and having relatively long fibrous material incorporated therein which lend the desired degree of strength to the strand material.

2. Packing material of the class described, 70 comprising macerated roofing scrap having relatively long fibrous material mixed therewith and formed into plastic rope-like strands.

3. Packing material of the class described 75 comprising macerated roofing scrap and relatively long fibrous material mixed therewith and formed into a plurality of intertwined plastic strands.

4. Packing material of the class described 80 comprising macerated roofing scrap having low melting point bituminous material mixed therewith, said mixture having relatively long fibrous material incorporated therewith, said mixture being formed into rope-like strands adapted to be conveniently used for packing purposes.

5. Packing material of the class described 85 comprising finely divided fibrous material, plastic bituminous material and relatively long fibrous material incorporated therewith, said materials being formed into a plurality of intertwined strands, the number of strands which are intertwined, being determined by the size of packing material 90 which is required.

In witness whereof, I have hereunto subscribed my name.
